WILLIAM CRUTCHLOW, OF PATERSON, NEW JERSEY, ASSIGNEE, BY MESNE ASSIGNMENTS, TO CROMPTON & KNOWLES LOOM WORKS, OF WORCESTER, MASSACHUSETTS, A CORPORATION OF MASSACHUSETTS.

BOX-OPERATING MECHANISM FOR LOOMS.

Application filed December 21, 1922. Serial No. 608,147.

This invention relates to looms in which the shuttle-box movements depend upon shifting of the shuttle-box-operating mechanism into position to be actuated by driving means in the loom, as in the case where said mechanism includes a vibrator gear journaled in a vibrator-lever between two mutilated cylinder gears forming part of the so-called driving means, said vibrator gear being brought into mesh with said gears, alternately, by shifting the lever. This shifting must take place when the shed is open in order to position the vibrator-gear in operative relation to one or the other of said mutilated cylinder gears, for rotation thereby (and consequent shifting of the boxes) upon the shed being closed; thus, with relation to shedding cycles each taken as extending from one full opening of the shed to the next, the shifting of the vibrator levers and gear should occur in the period comprising the fourth and first quarter-cycles and the rotation of the vibrator-gear is adapted to occur in the period comprising the second and third quarter-cycles. Heretofore it was regarded as impossible in a Jacquard loom to satisfactorily control or effect the shifting of the vibrator lever by the jacquard mechanism; instead, another pattern-controlled mechanism, as a dobby, was commonly used to shift the vibrator gears and thus control the box-operating mechanism. The difficulty attending any effort to utilize the jacquard machine for effecting the shifting lay principally in the fact that during an appreciable part of each period when the griff (or either griff) of the jacquard machine might act to effect the shifting (that is, during each lifting stroke of the machine) the shifting should not in fact occur at all because it was also then that the vibrator-gear should remain in raised or lowered position for rotation by one of the cylinder-gears to shift the boxes, or to state it otherwise: in the case of a double-lift machine a hook in the machine delegated to the shifting of the box-operating mechanism could not uninterruptedly remain caught on a griff during its active or lifting stroke because in the time covered by the second and third quarters of that stroke (i. e., of the cycle) said mechanism must stand stationary, since that is the box-changing period; and in the case of a

single-lift machine a hook so delegated could not be caught on the griff at the beginning of its active or lifting stroke because during the first half of that stroke (or third quarter) said mechanism must remain stationary.

In view of the foregoing it is my object to provide a construction by which the jacquard machine may control the vibrator-lever, thus making unnecessary the presence in the loom of additional pattern-controlled means for doing this work. And this I accomplish by the means hereinafter set forth, it being remarked that my invention is predicated upon utilizing an available part of the lifting stroke (as the fourth quarter-cycle) for performing a preliminary or setting operation, thereafter imposing the work of actually shifting said mechanism upon another member included in the driving means of the loom.

I have illustrated my invention in connection with a loom having a double-lift jacquard machine, but it will be understood that it is applicable to a loom having a single-lift machine.

In the drawings,

Fig. 1 is a front elevation of a loom containing my invention;

Fig. 2 is a similar view, on a larger scale, of the mechanism which I apply to the loom in order to effect the desired object;

Fig. 3 is a plan, partly in section, of what is shown in Fig. 2;

Fig. 4 is a side elevation showing principally the box-operating mechanism of the loom and certain connections embodied in the invention; and

Figs. 5 and 6 are diagrams.

In the loom frame *a* I have shown the usual driving means for a loom including the bottom or cam-shaft *b* having a double-crank *c*, two pitmen *d* connected with the double-crank, the levers *e* connected to said pitmen for raising and lowering the links *f* and therethrough the shed-forming elements or griffs *g* of a jacquard machine *h*. I have also shown gearing 23 connecting the cam-shaft *b* with the crank-shaft 22 of the loom so that said shaft 22 rotates in a 2 to 1 ratio with respect to the shaft *b* and gears *o o* (Fig. 4) intergeared by gears *p* so as to rotate in opposite directions at the same speed. The lower gear *o* is driven

from the cam-shaft b by a gear train o', o^2 , o^3 so that the gears o rotate in a 2 to 1 ratio with respect to the cam-shaft, said gears o having fixed to rotate therewith the mutilated cylinder gears q, q' (constituting actuators of the box-operating mechanism). The lower cylinder gear has a cam y fixed to rotate therewith for a purpose to be described. I also provide a gear 19 mounted 10 on the loom frame and having a wrist-pin 18 adjustable in a longitudinal slot in a crank arm 18' fixed to said gear, and a transmission gear 20 which is interposed between the gear 19 and the gear 21 on the crank-shaft 22 of the loom.

The jacquard machine is of well-known type and includes a plurality of hooks g' (Fig. 1) adapted to be connected to the warp threads and to be caught and elevated by one 20 or the other of the griffs g , and needles g'' through which the hooks are positioned with reference to the griffs, so that they will be caught and elevated thereby or will clear the same, as determined by a system of pattern 25 cards i' . A card cylinder i is arranged to rotate in a sliding structure h , and links j connect said structure with a lever l , said lever being connected with a third crank m on the cam-shaft b by a pitman n .

30 The shuttle boxes are shown at s (Fig. 1) as suitably slidable up and down in the ends of the lay s' , reciprocated in the usual way from the crank-shaft 22. The shuttle-box-operating mechanism is of well-known type 35 and includes the following parts: the mutilated vibrator-gears r (Fig. 4) journaled between the cylinder gears or actuators q, q' in vibrator-levers r' and movable with the latter into either of two positions where a selected vibrator gear may be engaged by one 40 or the other of said actuators q, q' ; and links t connecting eccentric points of the gears r with levers u forming a connection for transmitting motion to a compound lever v connected to the shuttle-box rod w . Associated 45 with this mechanism is the usual detent or lock-pawl z normally urged into locking engagement with the vibrator-levers by the spring z' and adapted on every revolution of cam y to be shifted clear of said vibrator-levers to allow the latter to be shifted up or down. It will be understood that in order 50 to obtain the four positions of the boxes required in the case of a 4 to 1 box-operating mechanism, here assumed, the parts q, q', r, r' , t and u must be duplicated.

In furtherance of my object I provide the loom with the following mechanism:

55 On the top of the loom frame is arranged an organization of parts known in the art as a "box indicator." It comprises a frame 60 2 (Fig. 2) two upstanding levers 3 which are respectively connected by flexible connections 4 with the vibrator-levers r' and each having a roller 3'; oscillatory cams 5

against the peripheries of which the rollers are respectively held by the weight of the vibrator-levers. Each cam has a recess 5' into which the roller may fall, so that when the cam is turned to the right in Fig. 2 70 and the roll falls into the recess, the associated vibrator-lever will be depressed but when the cam is turned to the left and the roller rises on the periphery of the cam the vibrator-lever will be elevated. The cams 75 are journaled on a shaft 6 in said frame; and opposed levers 7 are fulcrumed on said shaft and normally held spring-depressed against stops 7'. Either one of the levers 7, when elevated, engages the associated cam 80 5 at one of its lugs 5'' and shifts said cam one way or the other.

In a frame 8 (Fig. 2) suspended from the beams 9' (Fig. 1) on which the jacquard machine is arranged are fulcrumed four 85 levers 9 (Fig. 2) normally resting on stops 8' and connected respectively with the levers 7 by the flexible connections 10. These levers 9 are here shown in two pairs projecting oppositely from their fulcras and at their free ends they have reversely set upstanding pivoted couplings in the form of hooks 11, which by the weight of themselves and other parts connected to them normally stand inoperative or retracted against an intervening 90 stop 12. Each coupling or hook 11 is connected by a link 13 with a bell-crank lever 14 fulcrumed in frame 8 and each lever 14 is in turn connected by a flexible device 15 with one of the jacquard hooks g' , the 100 connection 15 being slack except when such hook is within the uppermost one-quarter of its vertical range of movement.

Frame 8 affords a fulcrum for a lever 16 having knives or lugs 17 to engage and lift 105 the hooks 11 when they are shifted from their retracted positions by pulls exerted by the jacquard hooks g' . This lever 16 which is a third actuator included in the drawing 110 means of the loom, is reciprocated by being connected with the wrist-pin 18 (Fig. 4). It is desirable that this connection between the lever 16 and the wrist-pin 18 should be a yielding one. Therefore there is a pitman 115 24 (Fig. 1) having a universal connection 120 with the lever and susceptible of axial movement in a yoke 25 (Fig. 4) which upwardly abuts a collar 26 on the pitman and downwardly abuts a spring 27 interposed between the yoke and a collar 28 on the pitman, the 125 yoke being pivoted on the wrist-pin 18.

Operation.

When any one of the jacquard hooks g' which are connected with the couplings or hooks 11 is called (i. e., coupled with a rising griff), there will then take place, during the last quarter of its rise or the last quarter of a cycle from one fully open shed to the next, a shifting of the corresponding 130

coupling 11 from its retracted position to operative position where it overhangs the corresponding knife 17. During the said cycle the lay s' has already received from the 5 crank-shaft its beating-up and return movement, so that the shuttle may be thereafter thrown when the shed is fully opened. As stated, the vibrator-lever must be shifted at about the end of this cycle, or at about the 10 time when the shed is fully open. The selected coupling 11 having been operatively positioned for effecting the shifting of the vibrator-lever, the lever 16 is then moved to raise its inner end by the downward pull 15 exerted by pitman 24, the gearing 21—20—19 being properly timed for the purpose. By this rising movement of the lever 16 the indicator mechanism (Fig. 2) puts the vibrator-lever in its new position and leaves it 20 there. On the return movement of the lever 16, the lever 7 simply returns idly to normal position in a manner characteristic of said mechanism. The same series of operations happens upon the calling of any other 25 hook or coupling g' of the jacquard machine that is devoted to controlling the vibrator-levers. Thus, while the jacquard machine does not shift the vibrator-levers directly, it does establish the condition 30 whereby such work will be done, and the actual work of so shifting the vibrator-levers is thereafter done by quite simple means, instead of by the complicated dobby mechanism previously used.

35 The yielding connection between lever 16 and wrist-pin 18 permits the throw of the latter to be more than enough to insure an adequate lift of any of the levers 7.

In further explanation of my invention I 40 may refer to Figs. 5 and 6, which diagrammatically illustrate the advantage derived from my invention in reference, respectively, to the lifting action of a double-lift and of a single lift jacquard machine.

45 In Fig. 5, one or the other griff moves (i. e., lifts) from A to B in coincidence with the period from one shed-opening to the next, and if a hook of the jacquard machine directly connected to shift a vibrator lever 50 were engaged with the griff during the first quarter (marked 1) of this movement, it would necessarily be disengaged immediately, as during the quarters marked 2 and 3, the vibrator-lever must stand at dwell; the 55 fourth quarter might be availed for the purpose of shifting the vibrator lever but the motion it affords is too small to effect reliably the full movement of the vibrator-lever, considering the distance from the Jacquard to the vibrator lever and the consequent lost motion.

In Fig. 6, the griff moves from A to B and back to A from one shed opening to the 60 next, and a hook delegated to the shifting of a vibrator-lever must be free from its

griff during the first half of the return or lifting stroke of the griff (or quarter marked 3) because during that quarter as well as during that marked 2 the vibrator-lever must stand at dwell. Here again 70 the first and fourth quarter is not satisfactorily available for the reasons already explained in connection with Fig. 5.

By my invention the fourth quarter is made available, as it is utilized only for obtaining motion which in the first place may be slight, though adequate for the purpose in hand, and in the second place only affects a part which presents inappreciable mass and which may be placed close enough to the 80 jacquard machine to substantially eliminate lost-motion.

There is much more flexibility in the timing of the several parts, as the lever 16 may operate at any time before the downward 85 movement of the griffs occurs, and the indicator mechanism may position the vibrator levers at any time during the engagement of the cam y by which the lock pawl is rendered inoperative.

Having thus described my invention and the operation thereof, I do not wish to be limited to the details herein disclosed otherwise than as set forth in the claims, but what I claim is:

1. In a drop box loom, a plurality of drop boxes, drop box actuating mechanism including a pair of cylinder gears, a plurality of vibrator gears and a plurality of vibrator levers supporting said vibrator gears, a drop 100 box indicator effective to selectively position said vibrator levers in raised or lowered positions and to retain said levers in such selected positions until said indicator is again operated, a regularly driven actuator 105 for said drop box indicator, a plurality of coupling members each normally maintained in withdrawn inoperative position but each movable at any time to position for engagement by said actuator and movable thereby 110 to render said drop box indicator operative to shift a selected vibrator lever, a jacquard mechanism and pattern controlled connections from said jacquard mechanism to said coupling members, whereby any one of said 115 coupling members may be selectively moved at any time into position for engagement by said actuator.

2. In a drop box loom, a plurality of drop boxes, drop box actuating mechanism including a pair of cylinder gears, a plurality of vibrator gears and a plurality of vibrator levers supporting said vibrator gears, a drop box indicator having angularly movable cams effective to selectively position said vibrator levers in raised or lowered positions and to retain said levers in such selected positions until said indicator is again operated, a regularly driven actuator for said drop box indicator, a pair 125

of oppositely disposed actuating levers for each cam, a coupling member for each actuating lever; said members being normally inoperative with respect to said actuator, a jacquard mechanism and pattern controlled connections from said jacquard mechanism to said coupling members, whereby said members, may be selectively moved into position for engagement by said actuator, 10 said connections including a plurality of hooks in said jacquard mechanism, each definitely assigned to control a selected coupling member and actuating lever, and effective to move one of said cams to change 15 the position of the associated vibrator lever.

3. In a drop box loom, a plurality of drop boxes, actuating mechanism therefor including a plurality of vibrator gears and levers, a drop box indicator connected to said vibrator levers and effective to selectively raise or lower said vibrator levers and to retain 20 said vibrator levers in such positions until said indicator is again actuated, said indicator having a plurality of actuating levers 25 each connected to a vibrator lever, a plurality of indicating levers for said actuating levers each having an operative movement and an idle return movement, means actuated by said indicating levers effective to move and retain the setting of each actuating lever, an actuator for said drop box indicator regularly moved in timed relation to the drop box actuating mechanism, coupling members connected to said indica-

tor levers and normally positioned inoperative with respect to said actuator, a jacquard mechanism, and pattern controlled connections from said jacquard mechanism to said coupling members effective to selectively position said members for engagement by 40 said actuator to control the ensuing movements of said vibrator levers. 35

4. In a drop box loom, a plurality of drop boxes, actuating mechanism therefor including a plurality of vibrator gears and levers, a drop box indicator connected to said vibrator levers and effective to selectively raise or lower said vibrator levers and to retain 45 said vibrator levers in such positions until said indicator is again actuated, said indicator having a plurality of levers each having an operative movement and an idle return movement, an actuator for said drop box indicator regularly moved in timed relation to the drop box actuating mechanism, 50 coupling members connected to said indicator levers, each normally positioned out of the path of and inoperative with respect to said actuator, a jacquard mechanism, hooks 55 in said jacquard mechanism each definitely assigned to control a selected coupling member, and a direct and positive connection between each hook and its associated coupling member through which said member is operatively positioned only so long as its jac- 60 quard hook is raised. 65

In testimony whereof I affix my signature.
WILLIAM CRUTCHLOW.
